[57] CLAIM

The ornamental design for an electronic calculator with solar batteries, as shown and described.

DESCRIPTION

FIG. 1 is a top plan view of an electronic calculator with solar batteries showing my new design;

FIG. 2 is a bottom plan view thereof;

FIG. 3 is a front elevational view thereof;

FIG. 4 is a rear elevational view thereof; and

FIG. 5 is a left side elevational view thereof, the right side being identical.
